FIG. 2

FIG. 3

FIG. 4

FIG. 5

FIG. 6

FIG. 7

FIG. 8

UNITED STATES PATENT AND TRADEMARK OFFICE
CERTIFICATE OF CORRECTION

PATENT NO. : Des. 487,438 S
DATED : March 9, 2004
INVENTOR(S) : Wei-Jong William Sheu

Page 1 of 1

It is certified that error appears in the above-identified patent and that said Letters Patent is hereby corrected as shown below:

Title page.

Item [73], Assignee, “**Nokia**, Espoo (FI)” has been replaced with -- **Nokia Corporation**, Espoo (FI) --.

Signed and Sealed this

Twenty-first Day of June, 2005

A handwritten signature in black ink, appearing to read "Jon W. Dudas". The signature is written in a cursive style with a large, stylized "J" and "W".

JON W. DUDAS
Director of the United States Patent and Trademark Office
